UNITED STATES PATENT OFFICE.

CLARENCE D. PLATT, OF BRIDGEPORT, CONNECTICUT.

KNIFE-SWITCH HANDLE.

No. 918,697.

Specification of Letters Patent. Patented April 20, 1909.

Application filed December 11, 1908. Serial No. 466,994.

To all whom it may concern:

Be it known that I, CLARENCE D. PLATT, a citizen of the United States, residing at Bridgeport, county of Fairfield, State of Connecticut, have invented a new and useful Knife-Switch Handle, of which the following is a specification.

This invention has for its object to provide a handle for knife switches which shall be especially adapted to meet the requirements of this use.

It is of course well understood that knife switches are apt to be operated quickly and with considerable force and that relatively great strain is placed upon the handles which are apt to become loose and when tightened up on the screws the tendency is to split the grips which are usually made of wood. My present invention enables me to overcome this difficulty and to provide a handle which is not liable to become loose or to split, which shall be inexpensive to produce and will stand all the hard usage to which handles of knife switches are liable to be subjected.

With these ends in view I have devised, the novel handle which I will now describe, referring to the accompanying drawing forming a portion of this specification and using reference characters to indicate the several parts.

Figure 1 is a plan view of the cross bar and blades of a knife switch with my novel handle in place thereon, partly in section, to show the construction and mode of attachment to the handle; Fig. 2 a similar view of the handle detached, showing the use in connection therewith of a spring washer; and Fig. 3 is a section of the cup-shaped spring washer detached.

10 denotes the cross bar and 11 the blades of a knife switch.

12 denotes the grip of the handle which is usually made of wood and may be of any ordinary or preferred configuration. At the inner end of the grip is the usual hub 13 for the reception of a ferrule, indicated by 14. It will be noted that the ferrule is made wider than the height of the hub, the inner end of the ferrule resting against a shoulder 15 on the handle and the other end projecting outward beyond the hub leaving a recess 16 at the end of the handle. The grip is secured in place by means of a double screw indicated as a whole by 17. The essential features of the screw are that the screw end there-

of has the configuration and thread of a wood screw, so called, indicated by 18, the cross bar end thereof has the thread of a metal screw, so called, indicated by 19, and intermediate threads 18 and 19 is a shoulder 20 which may be formed by swaging up the metal of the screw or may be formed separate and rigidly secured thereto. This shoulder is of less height than recess 16 so as to lie wholly within the recess. If preferred, a cup-shaped spring washer 21 may be interposed between the shoulder and the end of the hub of the grip. This washer when the grip is turned to place on thread 18 is forced out flat, as shown in Fig. 2, the tension of the washer acting to make a perfectly tight joint between the hub of the grip and the shoulder. In shipping, the handle is usually detached from the cross bar.

In setting up the switch for use, thread 19 is passed through the cross bar and the handle is retained in place by a nut 22, the nut being turned down tightly on the thread and drawing the end of the ferrule firmly against the cross bar but without contact of the shoulder with the cross bar. The action of the shoulder at all times is to prevent thread 18 from being forced downward into the grip with the necessary danger of splitting the grip. It will be obvious that when the nut is tightened on thread 19, the grip will be drawn toward the nut and the end of the ferrule will be forced against the cross bar. The shoulder, however, cannot come in contact with the cross bar, consequently there will be no tendency to split the grip, nor can the grip be turned farther on to thread 18 as it is stopped by the shoulder. The bearing of the washer on the cross bar makes the handle and cross bar perfectly rigid and provides a maximum of strength to resist the strains of use but without the placing of any undue strain on the connection of the grip with the wood screw thread.

Having thus described my invention, I claim:

1. A knife switch handle comprising a grip and a screw having at one end a wood screw thread for engagement by the grip, at the other end a metal screw thread for engagement with a cross bar and intermediate said threads a shoulder against which the end of the grip bears, substantially as described, for the purpose specified.

2. A knife switch handle comprising a grip having at its inner end a hub and below the

- hub a shoulder, a ferrule wider than the height of the hub and bearing against the shoulder leaving a recess at the end of the handle and a screw having at one end a wood screw thread for engagement by the grip, at the other end a metal screw thread for engagement with a cross bar and intermediate said threads a shoulder against which the end of the grip bears and which lies wholly within the recess.
3. A knife switch handle comprising a grip having at one end a hub, a ferrule wider than the hub whereby a recess is formed at the end of the handle, and a screw having at one end a wood screw thread for engagement by the grip, at the other end a metal screw thread for engagement with a cross bar and intermediate said threads a shoulder, and a spring washer lying between the shoulder and the end of the handle.
4. A knife switch handle comprising a grip

having a hub, a ferrule wider than the hub, a double-ended screw one end of which is engaged by the grip and the other is adapted to engage a cross bar, said screw having a shoulder intermediate the threads and lying within the ferrule against which the end of the grip bears.

5. A knife switch handle comprising a grip and a screw having at one end a wood screw thread for engagement by the grip, at the other end a metal screw thread for engagement with a cross bar and intermediate said threads a shoulder, substantially as described, for the purpose specified.

In testimony whereof I affix my signature, in presence of two witnesses.

CLARENCE D. PLATT.
